[57] CLAIM

The ornamental design for an automotive trim clip tool,
as shown.

DESCRIPTION

FIG. 1 is a perspective view of an automotive trim clip
tool showing my new design;

FIG. 2 is a top plan view thereof;

FIG. 3 is a side elevational view taken from the right of
FIG. 1;

FIG. 4 is a bottom plan view thereof;

FIG. 5 is an end elevational view thereof;

FIG. 6 is an end elevational view, opposite that seen in
FIG. 5.

FIG. 1

FIG. 2

FIG. 3

FIG. 4

FIG. 5

FIG. 6
